MEASURING PITCHER

Gerald Y. Sugai, 3379 Weatherford Court,
Simi Valley, Calif. 93063

Filed Apr. 18, 1974, Ser. No. 461,985

Term of patent 14 years

Int. Cl. D7—01

U.S. Cl. D7—64

FIG. 1

FIG. 2

FIG. 5

FIG. 4

FIG. 6

FIG. 3

FIG. 1 is a perspective view of a measuring pitcher, showing my new design;

FIG. 2 is a side view thereof;

FIG. 3 is another side view thereof;

FIG. 4 is another side view thereof;

FIG. 5 is a top plan view thereof; and

FIG. 6 is a bottom plan view thereof.

I claim:

The ornamental design for a measuring pitcher, substantially as shown.
